[57] CLAIM

The ornamental design for a supporting apparatus, as shown and described.

DESCRIPTION

FIG. 1 is a perspective view of a supporting apparatus showing our new design;

FIG. 2 is a top plan view thereof;

FIG. 3 is a front elevational view thereof;

FIG. 4 is a right side elevational view thereof, a left side elevational view thereof being a mirror image;

FIG. 5 is a bottom plan view thereof;

FIG. 6 is a rear elevational view thereof;

FIG. 7 is a perspective view of a second embodiment of FIG. 1;

FIG. 8 is a top plan view of FIG. 7;

FIG. 9 is a bottom plan view of FIG. 7; and,

FIG. 10 is a reduced perspective view of FIG. 7, the flower shown in broken lines for illustrative purposes only and forms no part of the claimed design.

The right and left side and rear elevational views of FIG. 7, are identical to those shown in FIGS. 4-6 respectively.
